UNITED STATES PATENT OFFICE.

HENRY WILLIAM SCHEILER, OF LAWNDALE, ILLINOIS.

SAFETY APPLIANCE FOR MINES.

982,095.

Specification of Letters Patent. Patented Jan. 17, 1911.

Application filed February 17, 1910. Serial No. 544,419.

To all whom it may concern:

Be it known that I, HENRY WILLIAM SCHEILER, a citizen of the United States, residing at Lawndale, in the county of Logan and State of Illinois, have invented certain new and useful Improvements in Safety Appliances for Mines; and I do hereby declare the following to be a full, clear, and exact description of the invention, such as will enable others skilled in the art to which it appertains to make and use the same.

This invention relates to improvements in safety appliances for mines, and the method of operating the same.

An object in view is the arrangement of an improved safety appliance for mines comprising a plurality of partitions or dams arranged in the various passageways, and each formed with one or more doors adapted to be closed and locked whenever desired for shutting off or localizing disturbances as explosions, fire, and the like.

A still further object of the invention is the arrangement of improved means for dividing mines into any desired number of sections, and furnishing all of the sections with water and compressed air after the sections have been cut off from the escape shaft.

With these and other objects in view the invention comprises certain novel constructions, combinations, and arrangement of parts as will be hereinafter more fully described and claimed.

In the accompanying drawings: Figure 1 discloses a view of the passage-ways of a mine with the safety appliance embodying the invention applied thereto. Fig. 2 is a view of a safety appliance arranged for operation in a single passage-way. Fig. 3 is a view similar to Fig. 2, but arranged for operation in a double passage-way. Fig. 4 is a slightly modified form of the invention disclosing a dam and a door arranged centrally thereof. Fig. 5 is a view of a construction similar to Fig. 4, except for use in a single passage-way. Fig. 6 is an enlarged detail perspective view of the framework of the door used both in the preferred form and the modified form. Fig. 7 is a detail view of the door used in the forms shown in Figs. 4 and 5.

In constructing and applying the device embodying the invention a plurality of partitions or dams are arranged in the entrées or passage-ways, so as to divide the various sections or parts of the mine into compart-

ments or sections. Each of these dams is provided with doors which may be readily closed for isolating any desired section. These doors are designed to be closed when 60 a fire, explosion, or the like has occurred, and the same cannot be put out or stopped. In addition to these doors and dams, a pair of pipes are arranged to extend throughout the mine and into every passage-way. One 65 of these pipes is adapted to carry water and the other compressed air. Suitable valves or hydrants are provided in both of these pipes at short intervals, and hose are also supplied near each hydrant so that the miners may fight the fire and if shut in at any time may be kept from smothering by turning on air from the air pipes.

In order that the invention may be more clearly understood an embodiment of the 75 same is shown in the accompanying drawings, in which 1 indicates the respective dams constructed of brick, preferably of the fire-proof variety. These dams are each built with a passage-way extending therethrough, 80 and may be of any desired length, though comparatively short. Arranged at each end of the passage-way in the dam is a framework 2. This framework 2 is formed of channel iron, as shown in Fig. 6, and is built 85 into the masonry in any desired manner. Also if desired the framework 2 may be secured by other means into the masonry or may be connected by beams 3 and 4. Hinged to the masonry 1 is a door 5 at each end of 90 the masonry designed to fit framework 2 when the door is closed. The door may be secured rigidly in position by suitable bolts after the same has been closed.

In Fig. 3 the structure is identical with 95 the structure shown in Fig. 2, except that it is duplicated for providing two passage-ways.

In Figs. 4 and 5 will be seen a slightly modified form of the invention, in which like characters will be used for similar parts, and additional characters will be used for the modified parts. Positioned in the masonry 1 of this form of the device is a door framework 2' substantially centrally of the masonry to which is secured, by suitable bolts, a door 5'. If desired the framework 2' may be set at an angle, as shown in Fig. 5. The door 5' is designed to be supported by members 6 and 7 and to be clamped in position 100 by suitable bolts passing through the door and engaging the framework 2'. In mount-

ing door 5' for resisting fire the door may be arranged on either side of the framework but when used to resist access of water the door is preferably put on the side of the framework from which the water is likely to come, as may be judged from differences of elevation or previous experience.

If desired a suitable packing could be used both in the preferred or modified form, so as to positively seal the door air-tight when the same is closed.

In addition to the dams and doors set forth a water pipe 8 and a compressed air pipe 9 are provided which extend throughout the various passage-ways in the mine, and are provided with suitable hydrants 10 and 11 at short intervals, so that if at any time anyone gets shut up by the closing of any of the doors there will be air and water at hand. To assist the miners in putting out fires, hose are arranged near the hydrants for application thereto and may be used as desired. The use of these water and air supplying means may not be confined to use in case of danger and absolute necessity, but may be used as desired during the normal operation of the mine.

What I claim is:

1. In a safety appliance system for mines, 30 an inclosed chamber extending across the haulway and being provided with doors for locking said chamber.
2. In a safety appliance system for mines, 35 an inclosed chamber extending across the haulway, said chamber being partitioned to form compartments and doors being provided for locking said compartments.

3. In a safety appliance system for mines, an arrangement of inclosed chambers extending across the haulways, and doors being provided for locking said chambers; said chambers dividing the mine into separate divisions and being constructed and adapted to withstand explosions, fires, and floods.

4. In safety appliance system for mines, 45 an arrangement of inclosed chambers extending across the haulways, and doors being provided for locking said chambers; said chambers dividing the mine into separate divisions and being constructed and adapted to withstand explosions, fires and floods; each division being separated from the rest of the mine by one or more chambers and any divisions being isolated from the rest of the mine by closing the doors of said one or more 50 chambers.

5. In safety appliance system for mines, an arrangement of inclosed chambers extending across the haulways, and doors being provided for locking said chambers; said chambers dividing the mine into divisions and being adapted to withstand explosions, fires and floods; of parallel pipes arranged closely, extending through said divisions and passing through the walls of said constructed 65 chambers to supply air and water to the divisions isolated by accidents.

In testimony whereof I affix my signature in presence of two witnesses.

HENRY WILLIAM SCHEILER.
